UNITED STATES PATENT OFFICE.

RUDOLF GRIESHABER, OF HOUSTON, TEXAS.

COLLAPSIBLE WARDROBE.

Application filed September 9, 1924. Serial No. 736,762.

This invention relates to improvements in collapsible wardrobes and has for its principal object to provide a simple and efficient device which may be readily and easily secured in position, the same being of such shape as to be supported in one corner of a room thereby occupying a minimum amount of space.

Another important object of the invention is to provide a collapsible wardrobe of the above mentioned character, which includes means for receiving and supporting various pieces of wearing apparel, a curtain being associated with the wardrobe whereby an unsightly appearance of the wardrobe is prevented and further forming an enclosure for suitcases or the like.

A still further object of the invention is to provide a collapsible wardrobe of the above mentioned character, wherein the same is of such construction as to enable a person to have ready access thereto at all times, the same being simple in construction, inexpensive, strong and durable and furthermore adapted for the purposes for which it is designated.

Other objects and advantages of this invention will become apparent during the course of the following description.

In the accompanying drawing forming a part of this specification and in which like numerals designate like parts throughout the same:

Figure 1 is a perspective view of my improved wardrobe showing the same secured in position in one corner of a room.

Figure 2 is a perspective view of the triangular shaped frame and the additional compartment carried thereby.

Figure 3 is a detail perspective view of the frame per se.

Figure 4 is a top plan view of the triangular shaped frame with the canvas top removed.

Figure 5 is a front elevation of the upper portion of the triangular shaped frame showing the segmental cooperating board sections in an upwardly disposed position.

Figure 6 is a detail sectional view through the front portion of the triangular shaped frame showing the manner in which the segmental board sections are secured to the frame.

Figure 7 is a fragmentary perspective view of the upper portion of the auxiliary frame.

Figure 8 is an elevational view of the triangular shaped frame showing the same in a collapsed or folded position, and

Figure 9 is a similar view with the curtain wrapped around the folded or collapsed frame.

In the drawings wherein for the purpose of illustration is shown the preferred embodiment of my invention, the numeral 1 designates generally the frame forming a part of the improved collapsible wardrobe and the same is substantially triangular in design and as is clearly illustrated in the drawing. The triangular shaped frame 1 includes the upper side bars 2 and 3 respectively which are spaced from the lower side bars 4 and 5 by means of the vertically extending members 6. In a similar manner, the front or base upper and lower bars 7 and 8 respectively are spaced from each other by means of the strips 9. Each of the front or base bars is hinged intermediate its ends as illustrated at 10 for the purposes hereinafter to be more fully described. The ends of the front or base bar are hingedly associated with the forward ends of the side bars in the manner as illustrated at 11 and 12 respectively and the adjacent ends of the side bars are hingedly connected together as 13. In this manner the triangular shaped frame 1 may be readily collapsed or folded into the position as shown in Figure 8 of the drawings.

For the purpose of maintaining the triangular shaped frame in its assembled position, the bracing members 14 and 15 are provided. The bracing member 14 extends between the bottom side bar 4 and the bottom front bar 8 while the brace 15 extends between the other lower or bottom side bar 5 and the intermediate portion of the brace 14. This construction is more clearly illustrated in Figures 3 and 4 of the drawings. The braces 14 and 15 furthermore afford a means for supporting coat hangers or the like on which are placed various pieces of wearing apparel.

Adapted to be stretched over the top and bottom of the frame are the pieces of canvas 16 and 17 respectively. Any suitable means may be provided for securing the canvas in proper position on the frame and as is clearly illustrated in Figure 4 of the drawing, the bottom canvas 17 is disposed over the braces 14 and 15. Similar pieces of canvas 18 cover the sides of the frame and

thereby forming a compartment for receiving hats or the like, it being understood of course that the front of the frame is open whereby access to the compartment may be had.

The triangular shaped frame 1 is adapted to be supported in one corner of a room a suitable distance above the floor in the manner as is clearly illustrated in Figure 1. For 10 this purpose, the ears 19 extend upwardly from the upper side bars 2 and 3 and provide a means for receiving fastening elements which are driven into the walls whereby the frame may be supported in a rigid 15 position in a corner.

Adapted to be detachably supported on the bottom of the frame 1 is the auxiliary frame designated generally by the numeral 20. The auxiliary frame comprises the upper angularly disposed bars 21 and 14, it being understood of course that the bar 14 also forms the brace between the lower side bar 4 and the lower front bar 8 of the triangular shaped frame 1 in the manner here- 25 tofore described. Hooks such as are shown at 22 are associated with the brace 14 and the bar 21 for attaching the same to the respective parts of the bottom of the frame 1. Ex- 30 tending downwardly from the brace 14 and the bar 21 are the pieces of canvas 23 and 24 respectively and triangular shaped shelves 25 and 26 are secured along their side edges to the canvas strips 23 and 24 intermediate the ends and adjacent the lower edges of the 35 canvas pieces respectively. The auxiliary frame provides a means for receiving small pieces of goods or linens and it is to be understood that the forward edges of the shelves 25 and 26 do not protrude beyond 40 the forward edge of the frame 1 for any appreciable distance.

Secured to the forward edge of the upper front bar 7 of the frame 1 are the seg- 45 mental sections 27 and 28 respectively. The segmental sections are preferably formed of wood and are hinged to the upper front bar 7 in the manner as illustrated at 29. Each section is disposed on the opposite side of the hinged connection 10 between the di- 50 vided front bars of the frame and for the purpose of normally holding the sections in a laterally disposed position with respect to the frame, a hook such as illustrated at 30 is associated with each of the sections and 55 is adapted for engagement with a suitable eye 31 secured to the vertical strips 9 ex- tending adjacent the hinged joint 10. This construction is more clearly illustrated in Figure 6 of the drawings. The adjacent 60 ends of the segmental sections 27 and 28 are cut in such a manner as to be arranged in interfitting relation, yet enable each of the sections to be swung upwardly independent- 65 ly of each other.

Secured on the under side of each of the

segmental sections is a curtain rod 32, the same providing means for supporting the upper edges of the curtains 33 and 34 respectively.

The curtain 33 covers substantially one-half 70 while the curtain 34 covers the other half of the frame and the curtain extends from the frame to the floor as is clearly illustrated in Figure 1. Each of the curtains is adapted for sliding movement on the curtain rods associated therewith so that access to the frame and the interior thereof may be had whenever desired.

When in position in a corner of a room as shown in Figure 1, a wardrobe is pro- 80 vided wherein the same may support various pieces of wearing apparel, the space between the bottom of the frame and the floor pro- viding a means for enabling garments to be hung on coat hangers or the like which are supported by braces 14 and 15 and suitcases and shoes may rest on the floor behind the curtains 33 and 34. A wardrobe of the above mentioned character, will occupy a minimum amount of space and may be readily col- 85 lapsed and folded into the positions shown in Figures 8 and 9 of the drawing, whereby all the parts comprising the wardrobe are wrapped in the curtains 33 and 34 and en- abling the same to be stored away when not 90 in use to further facilitate the carrying or transportation thereof. The simplicity in which my improved collapsible wardrobe is constructed enables the same to be man- 95 ufactured at a very low cost and will fur- 100 ther be strong and durable.

While I have shown the preferred embodiment of my invention, it is to be understood that various changes in the size, shape and arrangement of parts may be resorted to without departing from the spirit of the invention and the scope of the appended 105 claims.

Having thus described the invention, what I claim is:—

1. A collapsible wardrobe frame of tri- 110 angular formation when extended comprising a front including a pair of rectangular sections hinged together, a pair of rectangular shaped sides, means hinging the front ends of the sides to the outer ends of the front, lateral offset bars on the rear ends of the sides, and means hinging the bars together.

2. A collapsible wardrobe frame substan- 115 tially triangular in shape when extended comprising a front including a pair of rec- tangular sections hinged together, a pair of rectangular sides, means hinging the front ends of the sides to the ends of the front, laterally offset bars on the rear ends of the sides, means hinging the bars together, plates hingedly mounted on the upper rails of the rectangular front sections and adapted to have their edges in abutment when extend- 120 125 130

ed from the sections to prevent said sections from swinging in relation to each other.

3. A collapsible wardrobe frame of triangular form when in use comprising a front composed of a pair of rectangular frame sections hingedly connected together, a pair of rectangular sides, means hinging the front ends of the sides to the outer end portions of the front frame sections, angularly offset bars on the rear ends of said sides, means

hingedly connecting said bars together, a brace rod extending between and connected with an intermediate portion of one of said sides and the inner end portion of one of said front sections, and a similar brace rod 15 connected to the intermediate portion of the first-named rod and with the intermediate portion of the remaining side.

In testimony whereof I affix my signature.

RUDOLF GRIESHABER.
